LOCKING DEVICE

Walter R. Scherb, Silver Lake, N. Y., assignor to
 Western Electric Company, Incorporated, New
 York, N. Y., a corporation of New York

Application July 8, 1944, Serial No. 544,089

2 Claims. (Cl. 51—237)

This invention relates to a locking device, and more particularly to an arrangement for locking a member removably in place on a support.

In the manufacture of quartz crystal slices for use in electrical apparatus, the slices are often subjected to a lapping operation on the larger flat faces of the slices. To this end a crystal slice may be mounted on a holder whose body is cylindrical in form and on which holder the slice may remain through several operations including the one of lapping. The holder is clamped, for lapping, on a support operatively adjacent to a suitable lap and relative motion of the support and lap is employed to effect the lapping. To ensure suitably even reduction of the surface being lapped, it may be desirable to be able to change the angular position of the holder in the support with respect to the axis of the cylindrical body of the holder.

An object of the invention is to provide a device to hold a member, e. g. a cylindrical bodied crystal slice holder, securely but easily removably in place on a base member, e. g. a crystal holder support on a crystal lapping machine.

With the above and other objects in view, the invention may be embodied in a clamping device to exert pressure on an element to hold the same against a rigid support, a screw threaded base member to be received in a correspondingly threaded bore in the support, a clamp member mounted on the base member with freedom to reciprocate thereon axially thereof but without freedom to rotate therewith and dimensioned to overhang an element in position to be clamped against the support, resilient means to urge the clamp member along the base member away from the support, and means mounted on the base member and actuatable in one manner to force the clamp member toward the support to clamp an element thereagainst or to release the same and actuatable in another manner to rotate the base member to swing the clamp member to bring the clamping overhang thereof out of or into operative position.

Other objects and features of the invention will appear from the following detailed description of one embodiment thereof taken in connection with the accompanying drawings, in which the same reference numerals are applied to identical parts in the several figures and in which

Fig. 1 is a detached plan view with parts broken away of an illustrative embodiment of the invention;

Fig. 2 is a front elevation of the showing of Fig. 1, and

Fig. 3 is a section on the line 3—3 of Fig. 1.

As herein illustrated, the invention is shown as applied to the crystal holder support of a crystal lapping machine. Only this support is shown as the embodiment of the invention here disclosed requires no more for an understanding of the invention, other parts and the general function of the machine being no part of the invention.

So far as present purposes are concerned, the crystal holder support, generally indicated at 10, comprises a tabular member or table 11, triangularly symmetrical about the axis of a shaft 12, perpendicular to the table 11 at its center. The table 11 consists of three identically similar and identically similarly furnished sectors or lobes of which, therefore, only one is necessary to be described. The lobe in question presents a recess 14 in its periphery having the form, generally, of a right angled notch with its corner rounded off. Twin contact inserts 15, 15 of hard material, e. g. tungsten carbide, are mounted in the sides of the recess 14 to have their outer faces parallel to the sides of the recess but projected a little within the recess, all these parts being so arranged and dimensioned that the generally cylindrical body 16 of a crystal holder, when pressed sidewise into the recess 14 with the axis of the body 16 parallel to the axis of the shaft 12, will make contact against the inserts 15, 15 along elements of the cylindrical surface of the body about ninety degrees (90°) apart. Ordinarily there will be a positioning pin 17 rigidly mounted in the table 11 to project into the recess 14 along the bisector plane of the angle between the inserts 15, 15 and to enter alternatively into one or other of a plurality (here four) of slots 18 formed longitudinally in the surface of the body 16 to hold the body against rotation with respect to the table.

To releasably lock the body in the position shown, there is provided the device embodying the invention proper. This comprises a normally horizontal clamp member 20, whose left end is proportioned to overhang the recess 14 and is

provided with a pressure member 19 of more or less resilient material, e. g. leather, sponge rubber, or the like, arranged to lie tangentially against a body 16 in the recess 14. A bolt 21 having an elongated cylindrical head 22 provided with a transverse bore 23 is threadedly engaged in the table 11 beside the recess 14 to stand axially perpendicular to the normal length of the clamp 20, which is formed with a cylindrical bore 24, and with slots 25, 25 corresponding in size and location with the ends of the bore 23 in the bolt head 22, so that a pin 26 may be passed therethrough to lock the clamp 20 slidably on the bolt head 22. The right hand end of the clamp 20 is transversely bored and counterbored as shown to house two plungers 27 and springs 28 therefor held in place by threaded abutments 29, 29. The outer ends of the plungers abut against the table 11 and tend to urge the right hand end of the clamp 20 away from the table, and thereby tend to move the clamp 20 away from the table as far as the pin 26 in the slots 25 will allow the clamp to slide on the bolt head 22.

A cam lever 30 is formed as a yoke whose ends bestride the middle and left hand portions of the clamp 20, and are pivoted on the pin 26. The two pivot ends of the lever 30 are formed as cams 31, 31, as best shown in Fig. 1, so that, when the lever is in the position shown in full lines in Fig. 1, the cams 31 acting against abutments 32, 32 formed on the clamp 20 will drive the clamp 20 along the bolt head 22 toward the table 11 against the urge of the springs 28, whereas when the lever 30 is swung into the position shown in broken lines in Fig. 1, the clamp 20 is free to move away from the table along the bolt head 22 under the urge of the springs 28. The outer end of the lever 30 is preferably provided with a large transversely flat handle portion 33 having a finger hole 34. Between the table 11 and the clamp 20 there is a resilient washer 35 on the bolt 21, preferably of soft rubber or the like, to keep the clamp 20 from being cramped in its sliding on the bolt head 22 by the offset force of the springs 28.

In operation, assuming the various parts in the positions shown in solid lines in Fig. 1 and as shown in Figs. 2 and 3, and assuming that it is desired to rotate the crystal holder body 16 or to replace it by another, the lever 30 is swung forward to the position indicated in Fig. 1 in broken lines and is then turned on its axis clockwise. The finger hole 34 is to facilitate the first of these motions; and the broad flat blade-like handle 33 is provided to facilitate the second. Swinging the lever 30 forward as described releases the clamp 20 from the inward pressure of the cam 31; and the clamp 20 moves out on the bolt head 22 under the combined urges of the compressed rubber washer 35 and of the springs 28 until the washer is wholly uncompressed and the plunger 27 stops against the bottom of the counterbore 36 housing it in the clamp. The bolt head 22, the bore 24, the plunger 27, the counterbore 36, and the cams 31, 31 are all so proportioned and arranged that when the cams are withdrawn by turning the lever 30 forward to the broken line position, the pad 19 no longer presses against the crystal holder body 16, the washer 35 is no longer under pressure between the clamp 20 and the table 11, and the plunger 27 no longer presses against the table 11, although there may still be bare contact at one or more of the three points. Now rotating the lever 30 clockwise as one looks along its axis causes the lever, acting through the pin 26, to

turn the bolt 21 together with the entire assembly thereon and especially the clamp 20, thus swinging the left end of the clamp 20 up and to the right and clear of the opening of the recess 14. In the particular case illustrated, the bolt 21 and the bore 31, in which the bolt is held in the table 11, are formed with complementary left hand screw threads, so that, as the bolt is turned it also backs out of the table by a quarter of the pitch length of its thread, further ensuring the disengagement of the plungers 27 from the face of the table 11 and the release of pressure from the washer 35. The way is thus cleared to remove the crystal holder body 16 from the recess 14, to be turned as required and replaced with the pin 17 engaged in another of the slots 18, or to be replaced by another crystal holder.

The particular arrangement shown is designed to be revolved counterclockwise about the axis 20 of the shaft 12 to lap the crystals 38. Were this rotation in the other direction the necessary arrangement would be the mirror image of that shown and the bolt 21 would have a right hand instead of a left hand thread. The essential of this detail is that the bolt 21 must be so threaded that when the outswung lever 30 is turned to swing the padded end of the clamp 20 clear of the opening of the recess 14, the rotation of the bolt 21 thus effected will back the bolt a fractional turn out of its threaded housing and the plungers 27 will be drawn back positively out of contact with the table 11. Then, when the operation is reversed by turning the lever 30 counterclockwise, the plungers cannot overhang and snub on the edge of the table.

What is claimed is:

1. In an apparatus having a supporting member provided with rigid positioning means against which an article is to be pressed and clamped, the combination therewith of clamping means comprising a screw threaded bolt having a transverse bore in the head thereof, and engaged in a correspondingly threaded hole in the supporting member adjacent to the positioning means thereon, a clamping bar mounted on the head of the bolt to be slidable thereon axially of the bolt and to have one end overhang the positioning means, and formed with slots registering with the transverse bore in the head of the bolt and elongated axially of the bolt, a cam lever having one end thereof bifurcated and receiving the clamping bar therebetween and formed with bores registering with the bore in the head of the bolt, a pivot pin rigidly mounted in the bore in the head of the bolt and passing through the slots in the clamping bar to guide the same in axially sliding freedom of motion only on the bolt and engaged in the bores of the cam lever to provide a fulcrum therefor, cam surfaces formed on the cam lever to engage abutments formed on the clamping bar to move the same along the bolt head toward the positioning means in one position of the lever and release the same to be moved away from the positioning means in another position of the lever, a resilient contact pad mounted on the face of the clamping bar overhanging the positioning means, and a spring pressed plunger mounted in the opposite end of the clamping bar from the contact pad to engage and resiliently press against the supporting member.
2. In an apparatus having a supporting member provided with rigid positioning means against which an article is to be pressed and clamped, the combination therewith of clamping means

comprising a screw threaded bolt having a transverse bore in the head thereof, and engaged in a correspondingly threaded hole in the supporting member adjacent to the positioning means thereon, a clamping bar mounted on the head of the bolt to be slidable thereon axially of the bolt and to have one end overhang the positioning means, and formed with slots registering with the transverse bore in the head of the bolt and elongated axially of the bolt, a cam lever having one end thereof bifurcated and receiving the clamping bar therebetween and formed with bores registering with the bore in the head of the bolt, a pivot pin rigidly mounted in the bore in the head of the bolt and passing through the slots in the clamping bar to guide the same in axially sliding freedom of motion only on the

5 bolt and engaged in the bores of the cam lever to provide a fulcrum therefor, cam surfaces formed on the cam lever to engage abutments formed on the clamping bar to move the same along the bolt head toward the positioning means in one position of the lever and release the same to be moved away from the positioning means in another position of the lever, a resilient contact pad mounted on the face of the clamping bar overhanging the positioning means, a spring pressed plunger mounted in the opposite end of the clamping bar from the contact pad to engage and resiliently press against the supporting member, and a resiliently compressible collar about the shank of the bolt and interposed between the supporting member and the clamping bar.
